Primary Examiner — Christian P. Mclean

(57) **CLAIM**

The ornamental design for a lug nut removal tool as shown and described.

DESCRIPTION

FIG. 1 is a left side view of a lug nut removal tool, showing my new design.

FIG. 2 is a right side view of the claimed design.

FIG. 3 is a top view of the claimed design.

FIG. 4 is a bottom view of the claimed design.

FIG. 5 is a front view of the claimed design.

FIG. 6 is a rear view of the claimed design; and,

FIG. 7 is a perspective view of the claimed design.

The broken lines appearing on FIGS. 5 and 6 are of environmental matter, and form no part of the claimed design.

1 Claim, 3 Drawing Sheets(56)
